UNITED STATES PATENT OFFICE.

JULIUS S. STENERSEN, OF GARFIELD, UTAH.

SPRING CLOTHESPIN.

Application filed May 15, 1924. Serial No. 713,568.

To all whom it may concern:

Be it known that I, JULIUS S. STENERSEN, a citizen of the United States, residing at Garfield, in the county of Salt Lake and State of Utah, have invented certain new and useful Improvements in Spring Clothespins of which the following is a specification, reference being had to the accompanying drawings.

10 This invention relates to spring clothespins, and particularly to clothespins which open at one end to permit of their insertion upon a clothes line and which open at the opposite end so as to permit the jaws to 15 close upon articles to be supported on the line.

The general object of the invention is to provide a very simple and effective clothespin of this character wherein a passage is 20 made between the jaws of the clothespins for the line and the edges of which are provided with a groove and confronting tooth whereby the article will be more firmly gripped than is usually the case.

25 A further object is to improve upon the spring which causes the two elements of the pin to be held together.

A still further object is to provide means for locking the line within the pin and preventing any accidental detachment of the 30 pin from the line.

Other objects will appear in the course of the following description.

My invention is illustrated in the accompanying drawing, wherein:—

Figure 1 is an end elevation of a clothespin constructed in accordance with my invention;

40 Figure 2 is an inside face view of one of the members of the clothespin;

Figure 3 is a perspective view of one of the two members of the clothespin;

Figure 4 is a perspective view of the other member of the clothespin;

45 Figure 5 is a perspective view of the spring.

Referring to this drawing, 10 and 11 designate the two sections or members of the pin, these members at their upper ends 50 being beveled upon their inside faces, as at 12. At the intersection of these two beveled faces 12, the inside faces of the members 10 and 11 are transversely recessed so that together the two members define a clothes line

55 passage 13. One of the jaw members 10 is provided upon its inside face with an out-

wardly projecting rectangular tooth 14, while the other member is provided with a recess 15 with which this tooth normally engages.

The two members of the pin are held in resilient engagement with each other by a spring consisting of a transverse portion 16 which passes through conjoined recesses in the confronting faces of the pin below the passage 13, then that portion of the pin is bent into a volute, as at 17, and extended downward and laterally, as at 18, and then transversely, as at 19, so as to engage against the outer face of the corresponding clothespin jaw. This spring acts to hold the two sections 10 and 11 of the clothespin in engagement with each other and yet permits the jaws to be opened by pinching inward on the beveled ends of the clothespin. When 75 it is desired to insert this clothespin upon a line, the beveled ends are pulled outward, the jaw members fulcrumed at their lower ends, and the pin may then be inserted upon the line.

In order to prevent any accidental detachment of the pin from the line, I provide the transverse metallic pin 20 which extends through aligned passages 20* in the jaw members just above the passage 13 and 80 which, while permitting an opening movement of the jaw members, will prevent the pin from dropping off a clothes line when the jaw members are wedged apart at their upper ends. The downward strain upon 90 the clothespin often causes the line to wedge the upper end of the clothespin open and this would cause the pin to drop off the clothes line were it not for the locking pin 20.

95 In the use of this device and in order to string the clothespin upon a line, the locking pin 20 is removed, the upper ends of the clothespin are then pressed apart or forced apart by forcing the clothespin upward against the line, which causes the spreading of the upper ends of the pin, and then when the line is within the passage 13, the two sections of the pin spring together. The locking pin 20 is then re-inserted and, 100 of course, holds the clothespin against accidental detachment, as before explained, and then the clothespin is used in the manner that ordinary spring clothespins are used.

110 I claim:—

A clothespin of the character described

formed in two confronting sections, the upper ends of the sections on their inner faces being upwardly and outwardly beveled and the confronting faces just below said beveled portions being formed with confronting recesses defining a line passage, a spring urging the two sections against each other, and a locking pin extending loosely through and transversely of the sections just above the line passage, said pin being removable to permit the placement of the pin on a line but normally preventing the line from wedging the pin open.

In testimony whereof I hereunto affix my signature.

JULIUS S. STENERSEN.
